SUPPORT FOR SHOES MOUNTED UPON
LASTS

Frank Sbicca, Los Angeles, Calif.

Application June 10, 1946, Serial No. 675,586

3 Claims. (Cl. 211—34)

1

The present invention relates to shoe supports in general and more particularly to a support on which a shoe and a last are positioned during the time intervals between the successive steps in the process of shoe fabrication. More specifically the invention comprises a support on which an inverted shoe last and its enclosing shoe are positioned and supported in a manner which permits of easy removal and which eliminates contact of the shoe with exterior surfaces.

The manufacture of shoes comprises a series of operational steps in which the shoe, together with the last upon which it is assembled, are handled and rehandled, are laid aside while other units are worked upon, and are often moved from one location to another. For this purpose movable racks are provided, upon which the units, comprising a shoe and a last, are individually supported and by which they may be transported from place to place in the factory as desired. Such racks may be arranged so as to support the shoes in a single row or in a series of vertically spaced rows. Regardless of the particular arrangement, however, it is essential that the worker be able to position the shoes readily in the rack and also be able to remove them with the same ease therefrom.

These racks are used and reused and with the passage of time and much handling frequently become soiled with foreign material and if the shoes which are carried thereby come into contact with the soiled surfaces, they too are dirtied. Many shoes being light colored, soil marks thereon are clearly visible and to remove such marks requires a cleaning operation which might otherwise be unnecessary and the inclusion of which results in unnecessary manufacturing expense.

According to the present invention a shoe rack support is provided which is so constructed and arranged as to hold the shoe and its last in a manner that the surface of the shoe is entirely spaced from all adjacent surfaces. The last alone makes contact with the support or carrier when used with all standard shoe designs and the construction is further characterized by the ease and certainty with which the shoe and last unit may be positioned and removed.

It is accordingly an object of the present invention to provide a new and improved support for shoes and lasts during manufacture. It is another object of the invention to provide a carrier for shoes and lasts which supports the shoes out of contact with adjacent surfaces by which they could be soiled. It is a still further object

2

of the invention to provide a shoe rack in which shoes and lasts are removably positioned during the interval between steps in the process of shoe manufacture and which is characterized by the ease and certainty with which the units are positioned and removed.

These and other more specific objects will appear upon reading the following specification and claims and upon considering in connection therewith the attached drawings to which they relate.

Referring now to the drawings in which a preferred embodiment of the invention is illustrated:

15. Figure 1 is a view in perspective of a rack constructed in accordance with the present invention;

20. Figure 2 is a view showing the shoe and last about to be seated in its individual carrier or support; and

25. Figure 3 shows the shoe and last supported in the carrier.

In the drawings the reference character 10 indicates generally a portable shoe rack which is seen to comprise vertical uprights 11 at its opposite ends which are carried by bases 12, themselves adapted to rest or slide over a supporting surface. A plurality of vertically spaced shelves 13 extend between the end members 11. In the embodiment illustrated three shelves are employed but it is to be understood that the number of shelves, their length and their vertical spacing is entirely a matter of choice. Each shelf 13 is tilted slightly so that its upper surface makes an angle of about 15° with the horizontal, as is shown most clearly in Figure 3.

Along the upper surface of shelf 13 at regularly spaced intervals are supports or carriers 16, each of which is individually adapted to receive and support a shoe last 17 together with a shoe 18 by which it is enclosed and which is illustrative of a shoe in mid-process of manufacture. The general shape of the last 11 is standard and well-known, being a substantial imitation of the human foot with toe, heel and instep portions. The last is preferably made of a solid, relatively light material such as wood, and is shaped along its instep and heel to provide a pointed instep projection 21 and a flat upper heel area 22. Each carrier 16 is contoured and shaped to receive and seat a last 17 and comprises a flat plate 23, shaped generally as the sole of a shoe forward of the heel, and secured to its underlying shelf by a pair of screws 27 extended through openings 28. Forwardly and rear-

wardly positioned pairs of fingers 24 and 26, respectively, extend upwardly from the opposite sides of plate 23 at its front and rear extremities. The front arms or fingers 24 are longer and extend further above the plate than do fingers 26, but in each case the upper extremities are gently curved outwardly. Forward fingers 24, being parallel to the adjacent side of the plate 23, are angularly related, their included angle opening rearwardly, while the rear fingers extend 10 parallel. To receive the pointed projection 21 at the instep of the inverted last 17, plate 23 is formed with a V-shaped cut-out or opening 29, the rear edge or base of which lies along the edge 15 of the shelf 13, as shown in Figure 3, so as not to be obstructed thereby.

The carriers 16 arranged along the shelves 13 are identical and it will be necessary only to describe the relationship of one carrier to the shoe and the last unit positioned thereon in order to make clear the relationship which exists in each case. Let it be assumed that the last is positioned within the shoe and that the worker has been performing an operation thereon in the fabricating of the shoe. The same step is usually performed upon all of the shoes in a rack before a particular shoe in that rack is advanced to the next fabricating step. Upon completing the particular operation upon the shoe in his charge, the worker takes it by the underside and slides it and the enclosed last in an inverted condition into its empty carrier. The rack is turned so that the heels of the shoes face the operator and the movement of the shoe and last unit is forward and downward until the forward portion of the last instep seats between the front fingers 24 while the flat portion 22 of the heel rests between the rear fingers 26. The instep of the last is somewhat accentuated so that with its forward portion extended between the fingers 24 the pointed portion 21 thereof extends downwardly and rests against the base of the triangular cut-out opening 29 in the carrier plate 23. The shoe for its part is supported entirely by the last. The fingers 24 and 26 and the plate 23 entirely support and position the shoe and last by engagement with the latter only, while the enclosing shoe, which does not extend downwardly upon the last instep sufficiently to contact the fingers 24, nor sufficiently downwardly upon the heel of the last to contact the fingers 26, is supported entirely free therefrom. The carrier 16 is tipped slightly downwardly at its forward side, as shown in Figure 3, making for ease of positioning and removal, and, to an operator familiar with his work, the operation of replacing one shoe and last and withdrawing another is substantially a single continuous movement. He shoves the completed unit into its waiting carrier from the rear where it is retained by gravity and the cooperation of the parts as described. With his arm so advanced, he merely moves his hand laterally to grasp the adjacent shoe and last and pulls it rearwardly displacing it completely.

The carriers constructed in accordance with

the present invention are economically manufactured being simply made as by stamping from a single sheet of metal and are easily secured to and removed from their supporting shelf by the use of a screw driver.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. A shoe and last support adapted to seat a last formed with a narrowed downwardly extending instep and a shoe positioned thereon, comprising a plate formed with a central aperture to receive and seat the lower extremity of said instep with said last inverted, with spaced forward fingers constructed and arranged to receive and seat said instep forwardly of said lower extremity, and spaced rear fingers constructed and arranged to seat said last rearwardly of said instep.
2. A shoe and last support adapted to seat a last formed with a narrowed downwardly extending instep and a shoe positioned thereon, comprising a plate formed with a central aperture to receive and seat the lower extremity of said instep with said last inverted, with spaced angularly positioned fingers flaring slightly outwardly at their upper ends to receive and seat the instep forwardly of said lower extremity, and spaced fingers arranged rearwardly of said first-mentioned fingers flaring slightly outwardly at their upper ends and constructed and arranged to seat said last rearwardly of said instep.
3. A rack for shoes and lasts comprising a shelf, a support for inverted shoes and last mounted on the top of said shelf and extending forwardly therefrom, said support comprising a rigid base formed with a central aperture forwardly of said shelf to receive and seat the extremity of the last instep, a pair of forward fingers to receive and seat the forward portion of said instep, and a pair of rear fingers located above said shelf to receive and seat the heel of said last.
